United States Patent Office

Des. 185,130
Patented May 12, 1959

185,130

DESK TRAY

John B. Camilli, Weirton, W. Va.

Application July 18, 1958, Serial No. 51,834

Term of patent 14 years

(Cl. D74—1)

Figure 2 is a side elevational view, the side opposite thereto being substantially similar in appearance; and

I claim:

The ornamental design for a desk tray, as shown and described.
